UNITED STATES PATENT OFFICE.

RAMÓN LERA, OF BREMEN, GERMANY, ASSIGNOR TO HENRI BUCHY, OF MÜLHAUSEN-ELBASS, GERMANY.

GUARD-TENT FOR BABIES.

1,147,414.

Specification of Letters Patent. Patented July 20, 1915.

Application filed July 16, 1913, Serial No. 779,362. Renewed June 7, 1915. Serial No. 32,727.

To all whom it may concern:

Be it known that I, RAMÓN LERA, consul, citizen of the Mexican United States, residing at Bremen, Germany, have invented a certain new and useful Improved Guard-Tent for Babies, of which the following is a specification.

This invention proposes an improved guard tent for babies, which is so constructed as to enable the baby to move freely about therein without requiring supervision and without danger of becoming hurt by contact with any projections or parts of hard material, and which is specially designed to be set up in the open air.

It also comprehends a tent having the features specified which is capable of being readily collapsed, when desired, and folded up, so as to occupy but little space in storage or transport.

An embodiment of the invention is illustrated in the accompanying drawing, in which:

Figure 1 is a front elevation of the improved tent complete; Fig. 2 is a plan view of the base of the supporting frame; Fig. 3 is a plan view of the tent proper; and Fig. 4 is an enlarged perspective view.

In Figs. 2 and 3, the legs of the vertical member of the supporting frame are shown in section.

As shown in said drawing the invention, as a whole, consists of a tent proper, and a supporting frame therefor, the latter comprising, in turn, a base *a*, and a vertically-disposed bow *d*. The base *a* is here shown as rectangular and as having pivotally connected with its opposite side members the inturned ends *n* of the legs of the bow, although the said bow is normally held stationary by means of suitable pins *d'*, or the like, as depicted in Fig. 1. The connection of the bow ends *n* to the base *a* is effected by providing the outwardly-projecting central portions of the afore-mentioned side members of said base with inner and outer perforated lugs *a'* and *c*, through which said ends project, the said lugs being secured in any desired manner to the said base members. The outer lugs *c* are also formed with perforations through which, and through alining perforations in the legs of the bow, the pins *d'* are inserted. The tent proper is likewise rectangular in cross-section, as will be understood, and is composed of a

body of netting, secured at its lower edges to the base *a* and at its upper edges to an upper rectangular frame *b*, to which latter are also secured the edges of a top, cover or roof *f*, also made of netting. The side members of frame *b* are provided with laterally-projecting arms *b'* having terminal forks *m*, wherein rollers *m'* are mounted, which rollers are designed to travel along the inner sides of the legs of bow *d*, the said legs being formed adjacent their terminals *n* with outwardly-bent portions *o*, to facilitate the introduction of frame *b* and its arms *b'* into position with relation to the bow, and its removal from the same. The vertical edges of the tent body have ropes *h* attached to them, as shown, and these ropes are fastened at opposite ends to the corners of the frame *b* and base *a*, and are stretched by means of cords *e*, secured at their lower ends to the corners of frame *b* and having their upper ends connected together, the said connected ends being attached to a pull-cord or similar flexible operating element *g* that is led over a pulley *p* suspended from the top of the bow. In this way, the tent is maintained erect and in a tautened condition, as will be understood.

The tent body, as previously stated, is made of netting, preferably in two separate portions, the lower portion *l* being of relatively fine or narrow mesh, in order to prevent the baby from reaching through the same and picking up objects from the ground on the outside of the tent, while the upper portion *l* is of wider mesh, as shown in Figs. 1 and 4.

The floor of the tent preferably consists of a mattress *i* or the like.

The sides of the tent are equipped with roller shades *g*, which may be lowered when it is desired to screen the baby from the sun.

What is claimed is:

1. A guard tent for babies consisting in combination, of a supporting frame, comprising a base, and a bow extending thereover and connected at its ends thereto; and a collapsible tent proper suspended from the top of said bow and attached at its lower edges to said base. 100

2. A guard tent for babies consisting, in combination, of a supporting frame, comprising a base, a bow extending over the base and having the ends of its legs bent inwardly and pivotally and detachably con- 110

nected to said base at opposite points, and means for normally holding said bow in upright position; and a collapsible tent proper suspended from the top of said bow and attached at its lower edges to said base.

3. A guard tent for babies consisting, in combination, of a supporting frame, comprising a rectangular base having its opposite side members provided with centrally-located, inner and outer perforated lugs, a bow extending over the base and having its legs provided with inturned terminals which are pivotally and detachably engaged in the perforations in said lugs, and means removably engaged with said legs and the outer lugs for normally holding said bow in upright position; and a collapsible tent proper suspended from the top of said bow and attached at its lower edges to said base.

20 4. A guard tent for babies consisting, in combination, of a supporting frame comprising a base, and a bow extending thereover and connected at the ends of its legs thereto; and a collapsible tent comprising an upper frame suspended from the top of the bow, and a body of netting secured at

its upper and lower edges to said upper frame and said base.

5. A guard tent for babies consisting, in combination, of a supporting frame comprising a base, and a bow extending thereover and connected at the ends of its legs thereto; and a collapsible tent comprising an upper frame suspended from the top of the bow, and a body of netting secured at 30 its upper and lower edges to said upper frame and said base, said upper frame being provided with oppositely-projecting lateral arms having terminal rollers engaging said legs and adapted to travel therealong, 35 said legs having outturned portions adjacent their ends to permit of the positioning and removal of said upper frame and its arms.

In testimony whereof I have hereunto affixed my signature in the presence of two witnesses.

RAMÓN LERA.
